pany, Midland, Mich., a corporation of Dela-
wareNo Drawing. Application October 20, 1949,
Serial No. 122,578

4 Claims. (Cl. 260—600)

1

This invention relates to the production of hydroxy aldehydes, and, more particularly, to a method for oxidizing *o*-hydroxy benzyl alcohols to produce the corresponding *o*-hydroxy aldehydes.

It has been known that saligenin (*o*-hydroxy benzyl alcohol) can be oxidized to produce salicylaldehyde and salicylic acid. For example, Piria, Liebig's Annalen der Chimie, vol. 56, pages 42-43 (1845), and Trillat, Bulletin de la Societe Chimique, Third Series, vol. 29, page 45 (1903) disclose the oxidation of saligenin in the presence of platinum black, and Trillat states that saligenin is oxidized to salicylaldehyde in the presence of a platinum spiral. However, saligenin and its derivatives are readily oxidized to the acid; it is extremely difficult to conduct the oxidation in such a way that only the aldehyde is produced, and methods heretofore known for conducting such oxidation have resulted in comparatively low yields of the desired aldehydes. For example, saligenin has been oxidized by oxygen in the presence of platinum black, but it has not been found to be possible to convert more than five per cent of the saligenin to salicylaldehyde by this method. This oxidation has also been carried out (in air, in an oxygen atmosphere, under pressure; and in the absence of oxygen, as a dehydrogenation) in the presence of other catalysts (e. g., osmium, platinum oxide, platinum on zirconium oxide and platinum on pumice), but in no case has it been found to be possible to convert more than fifteen per cent of the saligenin to salicylaldehyde. The present invention is based upon the discovery of a new way for oxidizing saligenin or a substituted saligenin to the corresponding hydroxy aldehyde; the preferred embodiments of the new method can be used to effect a substantially greater yield of the desired aldehyde than has been achieved by the known method.

The principal object of the invention is to provide an improved method for producing salicylaldehyde or a substituted salicylaldehyde from saligenin or a substituted saligenin. More 45 specific objects and advantages are apparent from the description which illustrates and discloses but does not limit the invention.

In accordance with the invention an *o*-hydroxy aldehyde is produced from saligenin or a substituted saligenin. Saligenin and substituted saligenins are hereinafter for convenience called substituted phenols. The substituted phenols that are used have one ortho substituent of the formula $-\text{CH}_2\text{OH}$, any other substituent being a 55

halo, alkyl or alkoxy group. The substituted phenol is treated with a lower alkoxide of aluminum to form an aluminum derivative of the substituted phenol. The aluminum derivative is then oxidized by the action of a carbonyl-containing compound, and the pH of the resulting mixture is adjusted to convert the aluminum salt to the hydroxy aldehyde.

Although the invention is not limited to the theoretical explanation that follows, it is believed that the following reactions occur when the process of the invention is used to convert saligenin to salicylaldehyde:

(a) An aluminum derivative is formed by reaction between the saligenin and the lower alkoxide of aluminum; both the hydroxyls of saligenin form aluminum derivatives but each aluminum atom may react so that it is linked through oxygen, to one, two or three carbons of a benzene ring, as is illustrated by Equations 1 to 3, below,

3

in which R represents an alkyl radical.

(b) The desired oxidation is effected by the action of a carbonyl-containing compound on the aluminum derivative. This reaction is illustrated by Equation 4, below, which shows acetone as the carbonyl-containing compound.

(4)

(c) The desired o-hydroxy aldehyde is produced from the aluminum salt of the hydroxy aldehyde (shown as a product of Equation 4) by the action of an aqueous acid or by the action of an aqueous base followed by an aqueous acid.

As is illustrated by Equation 4, a dynamic equilibrium condition is approached when a substituted phenol and a carbonyl-containing compound are reacted. It is usually desirable that the reaction proceed substantially to the equilibrium condition; in this way approximately the maximum yield of product is achieved with a minimum of recycling. However, it is feasible to stop the reaction before equilibrium is reached and thereby shorten the reaction time. When reaction has proceeded to the desired extent, an aqueous acid or an aqueous base is added to the mixture to destroy the aluminum derivative and thereby to prevent further reaction in either direction. Equilibrium is achieved, under gentle reflux at atmospheric pressure, within about ten hours. Ordinarily there is no reason to maintain the reaction mixture under reflux after equilibrium is achieved, but the yield of product is not affected by so continuing. Usually it is desirable that the reaction mixture be refluxed for at least about four hours and preferred that it be refluxed for at least about six hours. Ordinarily, conducting the reaction of the invention at pressures other than atmospheric cannot be justified economically, so the maximum practical temperature is the reflux temperature at atmospheric pressure. It is, accordingly, usually desirable to conduct the reaction at about this temperature.

In general, as is hereinbefore stated, the method of the invention is used to convert saligenin or a substituted saligenin to salicylaldehyde or a substituted salicylaldehyde. Although the method can sometimes be used when the saligenin has other substituents, it is usually preferred that the starting material be saligenin or a halo-, alkyl-, or alkoxy-substituted saligenin. A particularly desirable embodiment of the in-

4

vention involves the use of a fluoro saligenin, most desirably 3-fluoro saligenin:

10 The fluoro-substituted salicylaldehydes, and particularly 3-fluoro salicylaldehyde:

15

which result when this starting material is used have particular utility in the production of oxygen-carrying chelates (see J. Am. Chem. Soc., vol. 68, p. 2254 et seq.). The halo substituents can be fluoro, chloro, bromo, or iodo. The alkyl substituent, or the alkyl part of the alkoxy substituent, can be primary, secondary, or tertiary; the number of carbon atoms is limited only by practical considerations, which usually make it desirable that the alkyl or alkoxy radicals have not more than about sixteen carbon atoms.

As has been indicated, an aluminum derivative of a substituted phenol is produced by treating the substituted phenol with an aluminum alkoxide. In general, the rate at which such derivatives are formed from an aluminum alkoxide is an inverse function of the molecular weight of the alkoxy group thereof. Accordingly, it is usually desirable that the aluminum alkoxide used be one in which the alkoxy radical is a lower alkoxy radical (i. e., has not more than five carbon atoms). As is indicated by Equations 1, 2 and 3, above, the alkoxy radical of the aluminum alkoxide is converted to the corresponding alcohol in the course of the formation of the aluminum derivative of the substituted phenol. Primary and secondary alcohols undergo oxidation reactions similar to that undergone by a substituted phenol in accordance with the invention. Accordingly, if the aluminum alkoxide used is one having a primary or secondary alkoxy radical, the alcohol produced therefrom should be completely separated from the reaction mixture before the carbonyl-containing compound is added thereto. Because tertiary alcohols do not undergo such an oxidation there is no need to remove tertiary alcohols so produced from tertiary alkoxy radicals, and the use of aluminum alkoxides comprising tertiary alkoxy radicals is a preferred embodiment of the invention. Aluminum tertiary-butoxide is the most advantageous material for such use because it is the most readily available and least expensive of those that yield tertiary alcohols. Ordinarily it is desirable that the molar ratio of the lower aluminum alkoxide to substituted phenol be from about 0.67 to about 3, and preferable that it be from about 1 to about 2.

In general, any carbonyl-containing organic compound (i. e., any ketone or aldehyde) can be used to convert the aluminum derivative of a substituted phenol to the aluminum salt of the corresponding hydroxy aldehyde. This is true because the carbonyl group is the part of the molecule effective in carrying out the desired oxidation, and substituents that are usually present with carbonyl groups do not interfere with the oxidation. For example, such vastly dif-

ferent carbonyl-containing compounds as acetone and o-chlorobenzaldehyde are shown by the examples to be effective carbonyl-containing compounds for the desired oxidation. Also, carbonyl-containing compounds in which a closed ring includes a carbonyl group as one of the constituents (e. g., benzoquinone, anthraquinone and cyclohexanone) are known to be effective for the desired oxidation. The preferred carbonyl-containing compounds for use in the practice of the invention have the general formula

in which R is hydrogen, or an alkyl, aralkyl, alkenyl, alkynyl, aryl or alkaryl radical. When R is anything other than hydrogen, the radical represented by R can be substituted with a halo or an alkoxy radical. R' is alkyl, aralkyl, alkenyl, alkynyl, aryl or alkaryl. R' can be substituted with a halo or an alkoxy radical. It is usually desirable that the total number of carbon atoms in each of the radicals R and R' be not more than twenty, and that there be not more than four halo substituents in either of these radicals. The halo substituent may be fluoro, chloro, bromo or iodo. Apparently, aldehydes are less stable, under the conditions used in the practice of the invention, than are ketones; for this reason aldehydes are more active oxidizing agents for use in the practice of the invention than are ketones. Because aldehydes are more active, the dynamic equilibrium illustrated by Equation 4, above proceeds farther (i. e., converts a larger percentage of the aluminum derivative of the substituted phenol to the aluminum salt of the hydroxy aldehyde) when an aldehyde rather than a ketone is the oxidizing agent. For this reason aldehydes are preferred carbonyl-containing compounds for use in the practice of the invention. The reaction is usually conducted under gentle reflux at atmospheric pressure, and it is desirable to use a substantial excess (e. g., from about 5 to about 100 mols of the carbonyl-containing compound, and preferably from about 10 to about 20 mols thereof, per mol of the substituted phenol charged) of the carbonyl-containing compound to drive the equilibrium represented by Equation 4, above, in the desired direction. Therefore, it is usually advantageous to use a relatively high boiling carbonyl-containing compound. Accordingly, aromatic aldehydes, being high boiling compounds, and being members of the active class of carbonyl-containing compounds (i. e., aldehydes) are particularly desirable carbon-containing compounds for use in the practice of the invention. It is usually desirable that the aromatic aldehyde have from one to two benzene nuclei, any substituents attached thereto being alkyl, alkoxy, or halo radicals. It is advantageous that no alkyl or alkoxy radical have more than six carbon atoms, and that the total number of carbon atoms in the aromatic aldehyde be not more than twenty. O-chlorobenzaldehyde is an example of this preferred class of carbonyl-containing compounds.

As is indicated by Equation 4, above, an aluminum salt of the desired hydroxy aldehyde is produced by means of the reaction between the carbonyl-containing compound and the substituted phenol. This aluminum salt is conveniently converted to the desired ortho-hydroxy aldehyde by (a) adding an aqueous acid to the reaction mixture or (b) adding an aqueous base

thereto and acidifying the salt formed. The organic material is then conveniently separated from the reaction mixture by a steam distillation or by solvent extraction. Since the desired oxidation reaction proceeds only between an aluminum derivative of a substituted phenol and a carbonyl-containing compound, the reaction is stopped by adding an aqueous acid or an aqueous base to the reaction mixture.

- 10 5 The following examples illustrate the new process, but are not to be construed as limiting the scope of the invention.

Example 1

- 15 15 An o-hydroxy aldehyde was produced from a substituted phenol according to the following procedure:

20 20 Aluminum isopropoxide (10 grams), 3-fluoro saligenin (2.84 grams) and tertiary butyl alcohol (500 cc.) were refluxed for three hours, and tertiary butyl alcohol (about 300 cc.) was then distilled, together with substantially all the isopropyl alcohol, from the resulting products. Acetone (500 grams) was added to the residue, and 25 25 the mixture so produced was refluxed gently for 20 hours, cooled, and filtered. The filtrate and sodium hydroxide (200 cc. of a 25 weight per cent aqueous solution) were then added to a distilling flask. The solids filtered from the reaction mixture were treated with sulfuric acid (50 cc. of a 10 weight per cent aqueous solution); when the aluminum complex had dissolved in the acid medium, the solution was made basic by the 30 30 addition of sodium hydroxide (about 20 cc. of a 25 weight per cent aqueous solution), and the resulting basic solution was combined with the filtrate and sodium hydroxide in the distilling flask. The entire mixture was heated until all alcohol, acetone, and other volatile organic matter was distilled. The residue from the distillation was then acidified with aqueous sulfuric acid and the desired products separated from the other materials by a steam distillation. A small amount of 3-fluoro salicylaldehyde separated 40 40 from the distillate of this steam distillation. The distillate was treated with toluidine (3 grams) in acetic acid (25 cc. of a 20 weight per cent aqueous solution). The Schiff's base so produced was separated by filtration and air dried. The 45 45 amount of Schiff's base recovered (0.20 gram) indicated a 4.4 per cent conversion of the 3-fluoro saligenin to 3-fluoro salicylaldehyde.

Example 2

- 55 55 A procedure similar to that described in Example 1 was used to produce 3-fluoro salicylaldehyde except that o-chloro-benzylaldehyde was used as the carbonyl containing compound. Aluminum isopropoxide (10 grams), 3-fluoro saligenin (2.84 grams) and tertiary butyl alcohol (500 cc.) were refluxed for about sixteen hours, and volatile material was then distilled to concentrate the solution to 100 cc. Tertiary butyl alcohol (300 cc.) and o-chlorobenzylaldehyde 60 60 (300 cc.) were added to the concentrate and the resulting mixture was refluxed gently for sixteen hours, cooled, and filtered. Sulfuric acid (200 cc. of a 10 weight per cent aqueous solution) was added to the cooled mixture, and the reaction mixture was then made alkaline by gradual additions of sodium hydroxide (a 50 weight per cent solution). The alkaline aqueous phase was separated from the organic phase in a separatory funnel, and the organic layer was then extracted 70 70 twice more with 10 weight per cent aqueous

sodium hydroxide (200 cc. portions). The three alkaline extracts were combined, and the resulting solution was steam distilled until no further organic material was detected in the distillate. The residue after this distillation was made acid with acetic acid, and p-toluidine (3 grams) in acetic acid (25 cc. of 20 weight per cent aqueous acid) was added to the acidified solution. The Schiff's base so precipitated, when separated and dried, amounted to 2.15 grams. This indicated a 47 per cent conversion of the 3-fluoro saligenin to the corresponding aldehyde.

Example 3

Aluminum tertiary butoxide was produced according to the following procedure:

A mixture of aluminum turnings (64 grams), mercuric chloride (0.5 gram) and tertiary butyl alcohol (200 grams) was refluxed gently. After refluxing for one hour additional tertiary butyl alcohol (a total of 150 grams) was added at such a rate that the exothermic reaction did not overheat the mixture. Refluxing was continued for an additional sixteen hours.

An excess of the aluminum tertiary butoxide produced as described in the preceding paragraph was mixed with 5-chloro-3-fluoro saligenin (35 grams), and o-chloro-benzylaldehyde (40 grams) was added. This mixture was held at a temperature between 70° C. and 80° C. for ten hours; the solids in the flask were dissolved by adding 10 weight per cent aqueous sulfuric acid; this solution was then made alkaline and steam distilled; and the residue was acidified and steam distilled to produce two grams of crude 5-chloro-3-fluoro salicylaldehyde.

We claim:

1. A method of producing an o-hydroxy aldehyde from a substituted phenol having (a) one ortho substituent of the formula $-\text{CH}_2\text{OH}$ and (b) not more than four other substituents each of which is of the class consisting of halo, alkyl and alkoxy, which method comprises (1) treating the substituted phenol with a lower alkoxide of aluminum to form an aluminum derivative of the substituted phenol; (2) subjecting the aluminum derivative to the action of a carbonyl-containing organic compound to produce an aluminum salt of the o-hydroxy aldehyde; and (3) adjusting the pH of the resulting mixture to convert the aluminum salt of the hydroxy aldehyde to the free hydroxy aldehyde.
2. A method of producing a halo-o-hydroxy aldehyde that comprises (1) treating a mono-halosaligenin with a lower alkoxide of aluminum to form an aluminum derivative of the halo-

saligenin, (2) subjecting the aluminum derivative to the action of a carbonyl-containing organic compound to produce an aluminum salt of the o-hydroxy aldehyde, and (3) adjusting the pH of the resulting mixture to convert the aluminum salt of the hydroxy aldehyde to the free hydroxy aldehyde.

3. A method of producing a fluoro-o-hydroxy aldehyde that comprises (1) treating a mono-fluorosaligenin with tertiary-butyl aluminate to form an aluminum derivative of the fluorosaligenin, (2) subjecting the aluminum derivative to the action of an aldehyde to produce an aluminum salt of the o-hydroxy aldehyde, and (3) adjusting the pH of the resulting mixture to convert the aluminum salt of the hydroxy aldehyde to the free hydroxy aldehyde.

4. A method of producing 3-fluorosalicylaldehyde that comprises (1) treating 3-fluorosaligenin with tertiary butyl aluminate to form an aluminum derivative of the fluorosaligenin, (2) subjecting the aluminum derivative to the action of an aromatic aldehyde to produce an aluminum salt of the o-hydroxy aldehyde, (3) adjusting the pH of the resulting mixture to convert the aluminum salt of the hydroxy aldehyde to the free hydroxy aldehyde, and separating the 3-fluorosalicylaldehyde.
